DESIGN FOR A RECEPTACLE FOR COSMETICS

Cecil H. Lawrence, Attleboro, Mass., assignor to Evans Case Company, a corporation of Massachusetts

Application November 16, 1940, Serial No. 96,642

Term of patent 3½ years

To all whom it may concern:

Be it known that I, Cecil H. Lawrence, a citizen of the United States, residing at Attleboro, county of Bristol and State of Massachusetts, have invented a new, original, and ornamental Design for a Receptacle for Cosmetics, of which the following is a specification, reference being had to the accompanying drawing forming a part thereof.

In the accompanying drawing,

In the article illustrated the side not shown is plain.

The dominant feature of my design resides in the ornamentation on the cover of the article shown in full lines in the drawing.

I claim:

The ornamental design for a receptacle for cosmetics, as shown and described.

CECIL H. LAWRENCE.
